UNITED STATES PATENT OFFICE.

LEVI H. LISTER, OF BAY ST. LOUIS, MISSISSIPPI, ASSIGNOR OF ONE-HALF TO WILLIAM H. BOUSLOG, OF GULFPORT, MISSISSIPPI.

REFRIGERATING-CAR.

1,072,131.

Specification of Letters Patent.

Patented Sept. 2, 1913.

Application filed July 26, 1912. Serial No. 711,687.

To all whom it may concern:

Be it known that I, Levi H. Lister, a citizen of the United States, residing at Bay St. Louis, in the county of Hancock and State of Mississippi, have invented certain new and useful Improvements in Refrigerating-Cars, of which the following is a specification.

The present invention relates to a refrigerating car of that type in which the ice chamber is located above the cooling chamber, so that the latter is cooled by the downward flow of cold air from the ice chamber. The ice is carried by a slatted or 10 perforated flooring or grating, so that a free circulation of air will take place through the same. In order to prevent the water from the melting ice from running down into the cooling chamber, a pan of metal or the like 15 is placed beneath the flooring which carries the ice, so that the water will be caught and may be carried off by way of a drain. Ventilators or openings of some kind are provided in the pan to permit a circulation of 20 air through the same, both up and down between the ice and cooling chambers, such ventilators or openings being so protected as to prevent the water from passing through them.

25 The cold water from the melting ice keeps the pan at approximately freezing temperature at all times, so that a very effective and uniform cooling takes place over the entire area of the pan. However, by reason of the low temperature of the pan, it has been found that moisture rising from the cooling chamber will be condensed and drip back into the cooling chamber, thus deteriorating 30 and even ruining fruits or meats therein contained.

One of the main objects of this invention is to provide a secondary or condensation pan in conjunction with that heretofore used, so that any condensation will be caught by 45 such secondary pan and will thus be prevented from dripping back into the cooling chamber. As herein illustrated, both pans really comprise a unit with an air space between them, but it will soon be apparent 50 that any other desired construction may be used.

Other objects and uses will appear from a detailed description of the invention, which consists in the features of construction and 55 combination of parts hereinafter described and claimed.

In the drawings: Figure 1 shows a plan section taken on line 1--1 of Fig. 2, looking in the direction of the arrows, portions of the ice slats being cut away, and a modified construction of flooring being shown in one corner of the figure; Fig. 2 shows a vertical section taken on the center line of the car, being the line 2--2 of Fig. 1 and looking in the direction of the arrows; Fig. 3 shows an enlarged cross section of the upper portion of the car, the same being taken on the center line 3--3 of Fig. 1, looking in the direction of the arrows; Fig. 4 shows a still further enlarged section through one side of the ice 60 flooring and pans, the same being taken on line 4--4 of Fig. 5 looking in the direction of the arrows; and Fig. 5 shows a section taken on line 5--5 of Fig. 4 looking in the direction of the arrows.

In the several figures, the car ends are designated by the numerals 6 and 7 respectively. The ice flooring 8 extends the entire width of the car and from the end 7 to the wall 9, thus providing the ice chamber 10. 65 The middle 11 of the partition is slightly higher than its ends 12 and 13, so that drainage will be toward the ends. The chamber 14 between the walls 6 and 9 can be dispensed with, if desired. The cooling chamber 70 is designated by the numeral 15.

The ice flooring comprises a plurality of longitudinally extending slats or bars 16, spaced apart in the manner presently to be described, to provide the spaces 17 between 75 consecutive slats, the air circulating up and down through the said spaces, and the water from the melting ice running down through them.

The construction thus far described is not 80 materially different from those heretofore used. In the present case, however, the flooring is divided up into a number of sections or units, the division illustrated being on the center lines 2--2 and 3--3, so that the 85 partition is in the form of four quarters. For this reason, the slats do not extend more than one-half the length of the car, so that each section will be independent of the others.

90 A number of L-shaped brackets 18 are secured to the side walls 19 and 20, at opposite points. The outstanding arm 21 of each bracket projects outwardly from the wall and supports one end of the channel-shaped cross member 22, the flanges 23 of 95 which closely engage the sides of such arm

21 and are preferably bolted thereto by the bolt 24. In this manner the cross pieces are securely held against displacement longitudinally of the car, but they can be easily removed by simply drawing the bolts and then lifting them until their flanges clear the brackets.

The water from the melting ice as it passes down between the slats is caught by 10 a pan or series of pans 25. In the construction illustrated, each of the pans covers one-fourth of the total area, thus corresponding to one section of the slats. Each pan has its sides and ends upturned, as at 26, a sufficient distance to effectively prevent an overflow of the water. The sides and ends are upturned all the way around each pan, so that each comprises a complete unit. Each pan, moreover, extends beneath all of the 20 slats of its section, the slats resting on it. For purposes of convenience, we will hereafter designate this pan as the "drip pan".

A second pan 27 is placed beneath each drip pan, but is spaced away therefrom to 25 provide a space 28. This pan likewise has its sides and ends 29 upturned a distance practically equal to that of the sides 26. The space 28 extends between the sides and ends of both pans, as well as between the 30 bottoms of them. For purposes of convenience we will hereafter designate this pan as the "condensation pan".

A series of perforations are provided in each pan, for permitting a free flow of air 35 between the ice and cooling chambers. It is preferred, for reasons which will herein-after be apparent, that the perforations in the drip and condensation pans should register, although this is not necessary. The 40 perforations in the drip pan are spaced in line with the spaces between the consecutive slats, so that they will extend in rows lengthwise of the car. A thimble 30 surrounds each perforation, extending above the bottom 25 of the drip pan and a sufficient distance to prevent leakage of the water from the melting ice through such perforation, a hood 31 being secured to the 45 top of each thimble, so that the water cannot drip down directly into it, such hood being supported above the upper edge of the thimble to provide a space 32 through which the air may circulate. A thimble 33 surrounds each of the holes in the condensation pan, and accomplishes a result similar to that 50 of the thimbles on the drip pan. In order to secure the most perfect circulation of air, the perforations in the drip and condensation pans line up with each other, and the 55 thimbles 33 extend up a slight distance into the thimbles 30. In this manner, a direct circulation of air may take place between the ice and cooling chambers, and with the least possible resistance, but, nevertheless, 60 a certain portion of the down-flowing cold

air will be deflected between the thimbles 30 and 33 to fill the space between the pans and thus lower the temperature of the same.

In an apparatus embodying the main features above described, it is found that practically all condensation will take place on the drip pan, and such condensation of course will drip into the condensation pan and be caught by it. It is found, moreover, that when using this construction, practically no condensation takes place on the lower surface of the condensation pan.

By reason of the fact that the pans are made up from a number of sections, their abutting edges on the center lines 2-2 and 3-3 should be protected, so that water from the melting ice will not pass down through the space between the center slats and enter directly into the spaces between the two pans. For this purpose, a hood 34 is placed over the edges of the pans on the center lines, as is well shown in Figs. 1 and 4. For the same reason, blocks 35 are extended out from the side and end walls of the car a sufficient distance to prevent ice from lying directly against such walls, and thus to prevent the water from entering directly between the walls and pans at their outer edges.

In order to space the pans apart the desired distance, and to transmit the load from the slats to the crosswise extending channels, spacer blocks 36 are provided between the pans. These are preferably placed in rows directly beneath the slats, and bolts 37 extend down through the slats, spacer blocks, and pans, to join all of these elements rigidly together. The bolts 38 which extend through these spacer blocks directly above the channels are passed also through the webs of the channels, so that the entire flooring, including the pans and slats, is rigidly secured to the channels and held against longitudinal displacement in cases of sudden impact. Spacer blocks 39 are placed between consecutive slats to retain them the desired distance apart, bolts 40 passing through all of the slats and spacer blocks of a given section.

From the above construction it will be seen that each quarter of the flooring is practically a self-contained unit, and can be removed from the car by simply removing the nuts from those bolts which extend through the channels, but without the necessity of removing them from the other bolts.

In the construction illustrated in Figs. 3, 4, and 5, each slat is provided with a T-bar 41, so that the completed slat is T-shaped. I do not limit myself to any such construction, however, but I contemplate within the scope of my invention any desired shape of slat. For example, in Fig. 1 I have cut away the top portions of a number of slats and have laid a screening 42 on them, such

screening preventing pieces of ice from dropping down between the slats, but at the same time permitting a proper circulation of air and perfect drainage.

5 It was previously stated that the ends of the slats at the center of the car should preferably be raised higher than their ends at the ends of the car, so as to permit the water to drain toward the ends. A drain pipe 43 is provided in each corner of the car, for carrying off the dripping water from each section of the flooring and pans.

10 I desire to call attention to the fact that by lining up the rows of pan perforations with the spaces between consecutive slats, the hoods or thimbles which protect such perforations may be extended up into the spaces between the slats, and thus the construction as a whole can be brought into a minimum of space, and can be made of a more permanent character than would otherwise be possible. Furthermore, in this manner the air movement is considerably improved, because the circulation is directly 15 to or from the perforations, with respect to the spaces between the slats. I desire also to call attention to the fact that, as far as I am aware, no other person has heretofore adapted a perforated drainage pan for use 20 in connection with an overhead ice-bunker or chamber for car service. It will be seen that a peculiar relationship exists between such a pan and overhead ice chamber for car service, in that the ventilation of the cooling 25 chamber is thereby greatly improved, and in that the cooling is much more efficiently and perfectly accomplished than would otherwise be possible. This is because of the fact that the water from the melting ice is 30 caught in the pan, thereby cooling the same over its entire surface, and thus securing a maximum of cooling effect in the chamber below, by reason of the direct contact of the air in such chamber with this large cooling 35 surface. Nevertheless, a great amount of cooling is secured by convection, because of the currents of air which are constantly circulating through the perforations in the drainage pans between the ice and the cooling 40 chambers.

50 I claim:

1. In a refrigerating car, the combination of a substantially horizontally extending ice partition having a plurality of longitudinally extending openings for the circulation of air, a drip pan mounted beneath said partition for the collection of water from melting ice, there being rows of perforations in the said drip pan registering 55 with the longitudinal openings of the partition, thimbles surrounding said perforations and extending upward into the lon-

60 gitudinal openings of the partition, whereby the drip pan may be mounted directly beneath the ice partition with its perforation thimbles extending up into the openings of the same, a condensation pan mounted beneath the drip pan and provided with openings in registry with the openings of the drip pan, and thimbles surrounding 65 the openings of the condensation pan and extending upwardly into the thimbles of the drip pan, whereby the condensation and drip pans may be mounted at a minimum 70 distance from the ice partition, substantially 75 as described.

2. In a refrigerating car, the combination of a substantially horizontally extending ice partition comprising a row of slats separated to provide longitudinal openings 80 between them, a drip pan mounted beneath said partition for the collection of water from melting ice, there being rows of perforations in the drip pan in registry with the openings between the slats of the ice 85 partition, thimbles surrounding said perforations and extending up into the openings between the slats of the partition, a condensation pan mounted beneath the drip pan for the collection of water of condensation therefrom, there being perforations in the condensation pan in registry with the perforations of the drip pan, and thimbles 90 surrounding the perforations of the condensation pan and extending upwardly into 95 the thimbles of the drip pan, substantially as described.

3. In a refrigerating car, the combination of a plurality of longitudinally extending ice supporting slats, a drip pan mounted immediately beneath said slats for the collection of water from melting ice, spacer blocks between consecutive slats and mounted with their lower edges above the drip pan for the purpose of permitting a free 100 flow of water lengthwise of the slats, tie rods extending through the several slats and spacer blocks to tie them rigidly together, a condensation pan mounted beneath and spaced away from the drip pan and 105 adapted to the collection of water of condensation, supporting blocks between the two pans and mounted in line with the ice supporting slats for the purpose of directly 110 sustaining the loads coming from the ice supporting slats, and tie rods extended vertically through the slats, supporting blocks, and pans, for the purpose of tying them together, substantially as described.

LEVI H. LISTER.
